IRONING BOARD

Samuel J. Bailey, Nicholson, Pa.

Application February 17, 1934, Serial No. 711,651

1 Claim. (Cl. 68—10)

This invention relates to ironing boards or the like, and has for its main object and feature the production of a device of this character which is of simple construction and compact when folded, which can be opened and latched in open position by a single movement, and which will afford a firm support when opened.

In the accompanying drawings the invention is shown in a concrete and preferred form in which:

Fig. 1 is a plan view of the underside of the ironing board with the parts in their folded position;

Fig. 2 is a side elevation with the parts in partly open position;

Fig. 3 is a side elevation with the parts in fully open position; and

Fig. 4 is a detail view of the latching means.

1 indicates a top of conventional character and 2 designates two rear legs pivotally connected at 3 to blocks 4 carried on the underside of the top. 5 indicates a front supporting means, here a single leg, pivotally connected at 6 to blocks 7 also carried on the underside of the top. It will be understood that the terms "rear legs" and "front supporting means" are relative and terms of description but not of limitation. 8 indicates rods that are pivotally connected at 9 to the rear legs at an intermediate point thereof, and at 10 to the lower end of the front supporting means. Two pairs of toggle links are interposed between the top and the rear legs. Each pair of toggle links consists of a relatively short link 11, pivotally mounted on a block 7 at one side of the front supporting means, but at a point 12 which is in advance of pivotal point 6 of said front supporting means, and a relatively long link 13 which is pivotally connected to the rear legs at 9 and to the short links at 14. Extending between the two short links 11 is a cross bar 15 and carried by the front supporting means is a self-locking latch 15a, here a gravity latch adapted to coat with said bar. 16 indicates diagonally extending cross braces connecting the rear legs.

When the parts are in their folded position, as indicated in Fig. 1, it will be seen that the rear legs, the front supporting means, the rods and

the toggles are all folded flat against the underside of the top, and it will be noted that the links of each pair of toggles lie side by side, the position of the short links 11 having been completely reversed from their extended position. It will also be noted that cross bar 15 tends to hold the front supporting means in its folded position, and that diagonal braces 16 serve the same purpose with respect to rods 8 and links 13. When the device is to be opened, the board is conveniently stood upon its rear end 11, front end 18 is grasped with one hand and front supporting means 5 with the other, and the two elements are drawn apart. In so doing, the rear legs, rods 8 and the toggles all follow the movement of the front supporting means, the short links 11 reverse their position and the toggles become extended. During this movement, cross bar 15 passes by latch 15a which drops down and prevents return movement. It will be noted that the toggle links pass slightly over the center when extended and that cross bar 15 engages front supporting means 5 and that taper surface 19 of the front supporting means engages the underside of the top. To fold the device, latch 15a is depressed when the parts can be returned to their collapsed position.

I claim:

An ironing table or the like including: a top; rear legs and front supporting means pivotally carried on and adapted to be folded against the underside of the top; rods pivotally connected to the rear legs and front supporting means and adapted to be folded against the underside of the top; two pairs of toggle links, one pair on each side of the pivotal point of the front supporting means, each pair of links so pivotally connected to the rear legs, to the top and to each other as to be extended when the legs are moved away from the underside of the top and, when said links are folded against the underside of the top, are completely reversed so that the links thereof lie side by side; a cross bar between the links of the two pairs of toggle links; and a self-locking latch on the front supporting means to coat with said bar.

SAMUEL J. BAILEY.
